UNITED STATES PATENT OFFICE.

ALFRED TRAPP, OF MILWAUKEE, WISCONSIN.

AUTOMATIC STABILIZING DEVICE.

1,416,911.

Specification of Letters Patent. Patented May 23, 1922.

Application filed September 21, 1921. Serial No. 502,373.

To all whom it may concern:

Be it known that I, ALFRED TRAPP, a citizen of the United States, residing at Milwaukee, county of Milwaukee, and State of Wisconsin, have invented new and useful Improvements in Automatic Stabilizing Devices, of which the following is a specification.

This invention relates to improvements in automatic stabilizing devices with particular reference to such devices as are adapted to be applied to ships.

It is the object of this invention to provide an automatic stabilizing device of such a character that it may be operatively installed upon a ship to preserve the cargo and passenger decks in a normal horizontal plane, regardless of the angles which the ship may assume in its passage across stormy seas. I am aware that it has hitherto been attempted to provide stabilizing devices adapted to maintain in a level position some small object, such as a table, chair or berth. Such devices of this nature as have hitherto been constructed have been unwieldy and have used an amount of space entirely disproportionate to the benefits derived from supporting so small an object. In the use of the present invention, the entire cargo carrying decks, and passenger state rooms as well, are maintained level by a device which is economical of the limited space available on board a ship. It is therefore the principal object of this invention to devise a construction which will be serviceably economical of space while obtaining for the entire contents of the vessel the stabilized effect desired.

In the drawings:

Fig. 1, is a side elevation of a ship provided with a stabilizing device, constructed in accordance with this invention, the hull of the ship being broken away to expose the interior construction.

Fig. 2, is a section taken on line 2—2 of Figure 1.

Fig. 3, is a plan view of the ship shown in Figure 1, with a portion of the upper deck broken away to expose the stabilizing devices.

Fig. 4, illustrates a modification of the stabilizing device shown in the previous views to adapt the device for passenger carrying vessels only.

Fig. 5, is an elevation of another side of the device shown in Figure 4.

Like parts are identified by the same reference characters throughout the several views.

A boat embodying this invention is provided with a hull constructed in any desired or appropriated manner. Transversely of the hull, adjacent its ends are located respectively bulk-heads 2 and 3. Journaled in bulk-heads 2 and 3 and preferably provided with a ball bearing therein, are the trunnions 5 and 6 upon which the stabilized decks hereinafter to be described have their longitudinal pivots. These trunnions support a longitudinally disposed frame work comprising transverse members 7 and 8 and longitudinal side members 9 and 10. It will be noted by reference to the drawings that the members 9 and 10 follow closely the outlines of the sides of the ship. It will, of course, be necessary in practice to construct these members 9 and 10 in the form of trusses or girders, since the entire weight of the decks and cargo is carried by them.

At a plurality of points along the longitudinal girder members just described are journaled the axes 11 of the cargo carrying units 12. It will be apparent that it is impossible to provide a single cargo carrying unit of the whole length of the ship since such a unit would be so long that if the ship began to pitch in a high sea, the ends of such unit would strike violently upon the hull at the bow and stern and might possibly inflict serious damage thereupon. To obviate this difficulty, I have provided a plurality of cargo carrying units 12, each of which is provided with a transverse pivot upon the axes 11 whereby each of said units can preserve its individual stability against the pitching of the ship hull, 1. The units 12 may be provided with a plurality of decks 13, each of which will constitute cargo carrying space. Access to these decks may be had through separate hatches provided in each unit 12.

In loading a ship constructed in accordance with this invention, the first and heaviest part of the cargo will preferably be placed upon the bottoms 14 of the several units. It will be apparent that this disposition of the cargo will prompt the utilization of the weight of said cargo in maintaining the whole device in a level or stabilized position. The weight represented by the bags 15 in the Figure 2, will not only maintain the unit 12 level fore and aft, but will also

aid in maintaining the whole frame work built up of the longitudinal side members 9 and 10 in a level position from side to side. Thus the upper decks of the several units 12

5 can be used for passenger carrying and for other purposes wherein considerable space is required for a little load, and such decks will be maintained level by the weight of the cargo in the lower parts of the units.

10 Obviously in the operation of a ship constructed in accordance with this invention, there will be no motion of the hull for which the swinging units 12 cannot automatically compensate themselves. When the hull is 15 pitching longitudinally, the units 12 will swing separately upon their transverse axes. When the hull is rolling from side to side, the units 12 will all move together upon the longitudinal axes of the frame work supported by trunnions 5 and 6. Supposing the 20 ship to be encountering a quarter sea, the trunnions 11, and 5 and 6 must both be used as pivots to allow units 12 to preserve their equilibrium.

25 It will be noted from the drawings accompanying this specification that the device embodying this invention is strictly economical of room. Units 12 appear to be disposed very close together, but it will be apparent that since they will always maintain parallel relationship between their ends, a very abnormal pitching of the ship would be necessary to bring the end members into contact. It will be understood that the illustration of the hull is purely diagrammatic, no ribs or other bracing being shown. If such bracing could be shown in the limited space available, it would be clear that there would be almost no waste space between the 30 hull and the bottom and sides of the units 12. This space, which is necessary to the proper construction of the hull of the ship, may be covered with a deck 16, adapted to register when the ship is on a level keel with the upper deck portion of each unit 12. It will be noted that the upper portions of said 35 units are rounded to conform to the arc of which the pivot of trunnions 5 and 6 is the center, so that the frame 9 and 10 can swing 40 the units 12 upon said pivot without disrupting the deck 16.

With reference now to the construction illustrated in Figures 4 and 5, it will be noted that I have here provided a frame work which is peculiarly adapted to be 45 mounted upon ships which are already in use to provide in such ships state rooms for the use of passengers who have a tendency toward sea-sickness. It is not sufficient to

give such passengers a berth which will maintain itself in a level position. The rolling of the state room about them is sufficient to produce the undesirable effect even though the passenger himself is maintained in equilibrium. It is therefore possible by 65 means of this modification of my invention to preserve whole state rooms in equilibrium for passengers with a tendency toward seasickness.

The device for holding model state rooms 70 in equilibrium preserving position includes a set of vertical uprights 20 and 21, within which are journaled the disc-like members 5' and 6' which correspond to the trunnions 5 and 6 of Figures 1, 2, and 3. Supported by 75 discs 5' and 6', upon a chord of said discs which is preferably located below the diameter thereof, is the longitudinal girder 9' which may be provided with such bracing as is necessary. Transversely disposed 80 across the longitudinal girder 9' are one or more transverse members 22 with downwardly turned ends 23, within which are journaled the discs 11'. These discs correspond to the trunnions or axes 11 of Figures 1, 2, and 3. Supported from the lower portion of discs 11' are the cabins 12' which include state rooms in groups of four or any other suitable number. The cabins 12' correspond to the cargo carrying units 12 of Figures 1, 2, and 3. It will be obvious that the vertical supports 5 and 6 may be located, if desired, at opposite ends of the ship with the girder member 9' extending longitudinally the full length of the ship and a 90 plurality of transverse members 12' in much the same way in which the units 12 are disposed in the construction illustrated in the 95 first three figures of the drawings.

The cabins 12', each of which may comprise a number of state rooms, are so supported by trunnions 5' and 6' and 11' that by their own weight they tend to keep themselves in equilibrium, turning upon pivots provided for them to compensate for the 100 motion of the ship upon which the device is mounted.

I claim:

The combination with the hull of a ship, of a frame work pivoted longitudinally of 110 said ship, and a plurality of cargo carrying units pivoted transversely of said frame work, said units being adapted to swing as one upon the longitudinal axis and to have independent pivotal movement upon their 115 several transverse axes

ALFRED TRAPP.
